UNITED STATES PATENT OFFICE.

GIDEON R. TAXIS, OF MORRIS, ASSIGNOR, BY DIRECT AND MESNE ASSIGNMENTS, TO THE COLEMAN HARDWARE COMPANY, OF CHICAGO, ILLINOIS.

SPRING-HINGE.

SPECIFICATION forming part of Letters Patent No. 434,212, dated August 12, 1890.

Application filed June 30, 1888. Serial No. 273,705. (Model.)

To all whom it may concern:

Be it known that I, GIDEON R. TAXIS, of Morris, Grundy county, Illinois, have invented certain new and useful Improvements in 5 Spring-Hinges, of which the following is a full, clear, and exact description, reference being had to the accompanying drawings, and to the letters of reference marked thereon.

The object of my invention is to provide a 10 simple and effective spring-hinge which is easily made and applied, and which, while little liable to get out of order, can be easily repaired.

In the drawings, Figure 1 is a perspective 15 view of my improved hinge. Fig. 2 is a side elevation thereof. Fig. 3 is a plan view, and Fig. 4 is a transverse sectional view.

Reference being had to the drawings, A and B represent two hinge plates or leaves of corresponding design and dimension. Each of 20 these plates has knuckles *a a*, extending from one end edge, and the knuckles *b b*, projecting from the other end edge. The location of these knuckles is such that when the plates 25 are united by the pintle C passing through them knuckle *a* of one plate will lap past and bear flat against knuckle *b* of the other plate. Knuckles *b* are preferably made thicker than knuckles *a*, and the surface 30 thereof against which thelapping end of knuckles *a* bears is sunk, so that the outer surfaces of the articulating knuckles of the plates may be in the same plane, and so that when the plates are in the position shown in 35 Fig. 1 the breasts of knuckles *a* and *b* will meet.

I do not claim anything new for the construction of the hinge-plates and knuckles, as just described, for such method of construction is common.

The new feature consists in the application 40 and combination therewith of the J-shaped torsional springs, which are similar in shape and dimensions and are preferably made of steel wire of suitable torsional strength. The 45 extremities of the shorter arm of the springs D and E are caught under and bear outward against the hook-shaped lugs *c c*, which face inward and are located near the outer longitudinal edge at about the center of length of 50 each plate. From these lugs *c* said springs pursue a longitudinal course toward and

pass under and around the hook-shaped lugs *d d*, which face outward and are located at the corners of plates D and E, diagonally opposite each other, and after making a bend 55 said springs pursue a longitudinal oblique upward substantially straight course to and into sockets *A'* and *B'*, projecting longitudinally parallel with the center of motion of said hinge-plate toward each other from 60 the knuckles *b b* of the plates A and B, respectively, as shown. These sockets *A'* and *B'* (as reference to the drawings will disclose) project from knuckles *b b* at corresponding points equidistantly removed from the 65 center of motion of the hinge-plates of the hinge, and are in the same longitudinal vertical plane as the pivotal center and spring E, the end of the longer arm of which enters socket *A'* (projecting from knuckle *b* of hinge- 70 plate A) in the reverse position to that of spring D, the end of the longer arm of which enters socket *B'*, projecting from the knuckle *b* of hinge-plate B. After the hinge-plates are connected by the pintle C passing through 75 the knuckles thereof, (said pintle having a head at one end and being screw-threaded at the other, so as to permit a thimble to be screwed thereon to retain it in place,) and after the springs D and E are placed in position, as described, said springs will, as the 80 plates are turned toward each other, be compressed, so that the ends of the substantially straight portions thereof will approach nearer each other until the sockets are in such position that straight lines drawn from their 85 respective centers to the center of oscillation of the hinge will be at right angles to each other. The compression of said springs will thereupon cease and expansion begins and 90 continues until the plates A and B are parallel with each other. The reverse of this proposition is equally true. Whichever way the plates are turned when the springs are compressed, there is resistance to the movement, and whenever the springs expand the 95 movement of the plates is assisted.

I do not wish to be confined to the use of a J-shaped spring in conjunction with my improved hinge, for a spring operating on the 100 same principle might be used which would correspond in length to the stretch of said J-

shaped spring between the socket and lug *d*, the end of which near where said lug *d* is stated to be, being secured to the plate in some other suitable manner at about the same 5 point. Lugs *d* and *e* or equivalent devices may be made integral with the plates, or otherwise secured thereto, as desired.

What I claim as new is—

In a spring-hinge, the combination of the 10 hinge-plates A B, having lugs *c* and *d*, and having knuckles *a* and *b*, the latter of which have inwardly-projecting sockets *B'* and *A'*, and pintle C, connecting said knuckles, so that

the knuckles *a* of one plate lap outside of the knuckles *b* of the other plate, and the J-shaped 15 torsional springs D and E, the shorter arm of each of which is secured by lugs *d* and *c* of one plate, and the longer arm of which pursues an oblique longitudinal course from lug *d* to the socket projecting from the knuckles *b* of the 20 other plate, as and for the purpose set forth.

GIDEON R. TAXIS.
